UNITED STATES PATENT OFFICE

108,777

DESIGN FOR A TYPEWRITER

Richmond L. Chipman, Jr., Montclair, N. J., and
Joseph Lee Sweeney, New York, N. Y., as
signors to Bates Laboratories, Inc., New York,
N. Y.

Application April 8, 1937, Serial No. 68,636

Term of patent 14 years

To all whom it may concern:

Be it known that we, Richmond L. Chipman, Jr., a citizen of the United States, residing at Montclair, New Jersey, and Joseph Lee Sweeney, a citizen of the United States, residing at New York, New York, have invented a new, original, and ornamental Design for Typewriters, of which the following is a specification, reference being had to the accompanying drawings, forming part thereof.

Fig. 1 is a perspective view of a typewriter,

showing our new design; and Fig. 2 is a side elevational view, thereof.

Fig. 3 is a top plan view thereof.

The invention resides in the parts shown in full lines.

We claim:

The ornamental design for a typewriter, as shown and described.

RICHMOND L. CHIPMAN, JR.
J. LEE SWEENEY.
